UNITED STATES PATENT OFFICE.

CECIL C. ABBOTT, OF HARBOR SPRINGS, AND WILLARD EARL BASSETT, BERT L. BASSETT, AND IRVIN L. BASSETT, OF DETROIT, MICHIGAN.

FIRE ESCAPE.

Application filed July 13, 1921. Serial No. 484,403.

To all whom it may concern:

Be it known that we, CECIL C. ABBOTT, a resident of Harbor Springs, Michigan, and WILLARD E. BASSETT, BERT L. BASSETT, and 5 IRVIN L. BASSETT, residents of Detroit, Michigan, all citizens of the United States of America, have invented certain new and useful Improvements in Fire Escapes, of which the following is a specification.

10 This invention relates to fire escapes and has special reference to portable fire escapes which may be anchored within a room when use of the same is necessary, and operated to lower a person from a window of the room 15 to the ground. An object of our invention is to provide a fire escape which may be readily returned to the room when it has been relieved of the weight of a person so that another occupant of the room may escape. The invention resides in certain novel 20 features which are illustrated in the accompanying drawings and hereinafter fully set forth.

In the drawings—

25 Figure 1 is a side elevation, partly broken away, of our improved fire escape;

Fig. 2 is a central horizontal section;

Fig. 3 is a transverse section with parts in elevation;

30 Fig. 4 is a detail section.

In carrying out our invention, we employ an outer casing 1 which is provided with an eye or hook 2 adapted to be engaged over a bedpost or some fixed object adjacent a window of a room. This casing is provided at a 35 point diametrically opposite the hook or eye 2 with a slot 3 through which the tape or cable 4 passes, the said tape or cable being equipped at its free end with a belt to be 40 passed around the body of the person using the escape. The tape is wound within a drum 5 and has its inner end secured to the hub 6 of the drum, said hub being keyed to one end of the main shaft 7 supported in the 45 walls 8 of an inner supporting frame and in partitions or plates 9 forming a part of the supporting frame. The partitions 9 divide the casing into a tape or cable chamber containing the drum 5 and the cable 4, and 50 working chambers containing the operating mechanism. Upon that portion of the shaft 7 which is disposed in the working chamber, a ratchet wheel or collar 10 is fitted upon the shaft so that it may slide longitudinally 55 of the same but is constrained to rotate therewith and a spring 11 is coiled around the shaft 7 between the said ratchet and the adjacent side plate 8, as shown clearly in Figs. 2 and 4. This ratchet 10 engages a mating ratchet 12 which is fast to a gear 60 wheel 13 fitted loosely upon the shaft 7, as shown, a pinion 14 being arranged concentric with the shaft between the partitions 9 and secured to the hub 6, as shown most clearly in Fig. 4. 65

The gear wheel 13 meshes with a pinion 15 which is carried by a countershaft suitably journaled in the plate 8 and the partition 9 more remote from the drum 5 and also carrying a gear wheel 16 which meshes with 70 a pinion 17 on the governor shaft 18. The said governor shaft is journaled in the inner end wall of a governor casing or drum 19, the peripheral wall of the casing being secured rigidly to the plate 8, and the end of 75 the shaft 18 within the casing actuating governor arms or braking shoes of any preferred form which will swing outwardly under centrifugal action, when the shaft is rotated, to bear upon the inner surface of 80 the peripheral wall of the brake drum with a binding action and thereby retard the descent of the person using the fire escape. When the device is in use, the unwinding of the tape or cable 4 will impart motion 85 to the shaft 7 and this motion will be transmitted through the described gearing to the governor shaft 18. As the speed increases, the governor arms or shoes will move apart under centrifugal action and bear upon the 90 peripheral wall of the governor casing, as stated. The speed of the parts will, therefore, be checked and the person using the device will be lowered gradually to the ground so that he will not be injured through 95 too rapid descent and sudden contact with the ground. When the cable 4 is rewound, the ratchet member 10 will work loosely upon the ratchet member 12 and ride over the same so that the governor will not be 100 operated.

To rewind the cable or tape 4, we provide a winding crank 20, the hub 21 of which is fitted loosely upon the end of the shaft 7 remote from the drum 5, said end of the shaft being extended through the side of the casing 1 to receive the hub 21. Upon said hub 21 is fixed a pinion 22 which meshes with a gear 23 on a countershaft 24 which is journaled in the adjacent side wall 110

105

110

8 and the partitions 9, the pinion 22 and gear 23 being arranged between the wall 8 and the side of the casing. Upon the inner end of the countershaft, between the partitions 9, is secured a gear 25 which meshes with the gear 14. Consequently, when the crank handle 20 is turned, motion is imparted to the pinion 22 and transmitted through the gears 23, 25 and 14 to the drum 10 so as to wind the cable, the ratchets slipping past each other so that the brake is inactive.

It will be readily noted that we have provided a very compact, simple and efficient device which may be readily used by unskilled persons and which may be manufactured at a low cost. The governor will effectually retard the descent of the person using the device and acts with the same efficiency whether the escaping person is 20 light or heavy.

After the first user of the device has reached the ground, another occupant of the room turns the crank so as to rewind the cable and thereby return the belt so that the 25 device may be again used.

Having thus described the invention, what is claimed as new is:

A fire escape comprising a casing, a frame within the casing and including a pair of 30 side walls and a pair of partitions between and parallel with the side walls, a shaft extending through the frame and one side of the casing, a drum secured on the inner end of said shaft between one side wall and one

partition of the frame, a gear disposed between the partitions and rigid with the shaft and the drum, a governor arranged adjacent the side wall of the frame remote from the drum, a train of gearing connecting the shaft with the governor and including a gear loose upon the shaft, all the members of said train of gearing being located between the last-mentioned side wall of the frame and the adjacent partition, a ratchet rigid with the side of said loose gear, a mating ratchet 45 slidably mounted on the shaft and constrained to rotate therewith, yieldable means acting upon the slidably mounted ratchet and tending constantly to hold the two ratchets in engagement, a winding handle 50 loosely fitted on the shaft exteriorly of the casing, a pinion rigid with said handle and disposed between the casing and the adjacent side wall of the frame, a countershaft extending through the frame, and gears on 55 said countershaft, one of said gears being disposed between the partitions of the frame and meshing with the gear which is rigid with the drum and another gear being disposed between the side of the casing and the frame and meshing with the pinion which is rigid with the winding handle.

In testimony whereof we affix our signatures.
